UNITED STATES PATENT OFFICE.

ALBERT BUCHNER AND ELMER P. McCLURE, OF CHICAGO, ILLINOIS.

JOURNAL-BEARING.

No. 820,765.

Specification of Letters Patent.

Patented May 15, 1906.

Application filed August 6, 1902. Renewed September 25, 1905. Serial No. 280,055.

To all whom it may concern:

Be it known that we, ALBERT BUCHNER and ELMER P. McCLURE, citizens of the United States, residing at Chicago, in the 5 county of Cook and State of Illinois, have invented certain new and useful Improvements in Journal-Bearings; and we do hereby declare the following to be a full, clear, and exact description of the invention, such as will 10 enable others skilled in the art to which it appertains to make and use the same.

This invention relates to improvements in that class of motors or vapor-engines in which the crank works in an air-tight chamber, and has for its object to provide a journal-bearing arrangement for the crank-shaft whereby it is easily adjusted to compensate for the wear and at the same time maintain a tight joint and prevent the explosive mixture 20 escaping from the crank-chamber through the bearings.

In the drawings, Figure 1 is an elevation and part section embodying the improved features; and Fig. 2 is a side elevation and 25 section on line 2, Fig. 1, looking in the direction indicated by the arrow.

It will be understood that the motor or engine may be of any or the usual construction. The description will therefore be con- 30 tinued to the improved features.

A represents the cylinder; B, the crank-shaft; C, the companion fly-wheels, and D the crank-chamber in the supporting-base E. The two open sides of the crank-chamber are 35 closed by tight-jointed bearing side plates or caps 3, and as the bearings and parts on each side are alike a description of one side will answer for both. The outside journal pillow-block 4 is cast solidly with and forms 40 an integral part of the side plates 3. This outside pillow consists of a bottom part 5 and the extended arched top part 6. A space 7 under the arch provides for the endwise insertion and adjustment of a loose journal- 45 cap 8. The adjusting-screws 9 are inserted down through the arch part 6 with a thread-ed engagement therein and bear loosely on the journal-cap 8. These screws are pro- 50 vided with the usual lock-nuts 10 for retaining the same in their set position.

The metal boxes or bearing proper comprises the lower semicircular box 11 and the corresponding upper half 12, inclosing the crank-shaft, which passes through both of the side plates. A great deal of trouble and 55 inconvenience has been met with in this class of motors in providing proper means for conveniently compensating for the wear and maintain a close uniform contact of the bearing-surfaces and at the same time prevent the escape of any portion of the explosive mixture therethrough from the crank-chamber.

By this arrangement a continuous uniform bearing may be maintained and the 65 journal-cap adjusted to a nicety, so that the wear is more equally distributed and the motor operated for a longer time before the boxes and crank-shaft get out of line than is possible under the ordinary arrangement. 70 The outside journal-box is provided with an extension 13, threaded, as at a, for the engagement of the packing-gland 14 in forming the usual stuffing-box 15 in providing a tight joint around the crank-shaft.

Having thus described our invention, what we claim, and desire to secure by Letters Patent, is—

1. A journal-bearing of the class described, comprising a chambered base, the companion side plates provided with a pillow-block having an arched top open from the inner end, an adjustable journal-cap inserted therein, and means employed in connection with the arched top for holding the journal-cap 80 to a uniform bearing, substantially as set forth.

2. In a journal-bearing of the class de- 85 scribed, the combination with a chambered base open on opposite sides, of companion side plates having an integral pillow-block and an arched top over the bearing with an intervening space, a journal - cap inserted endwise in said space, and means for retaining said cap in a uniform bearing position in 95 compensating for the wear, substantially as set forth.

3. In a journal-bearing for gas-engines, the combination with a chambered base open on oposite sides, of a crank-shaft inserted 100

therethrough, the companion side plates closing the open sides and provided with a pillow-block having an arched top and a stuffing-box extension, the journal-cap inserted loosely in its bearing position, and the 5 adjusting-screws bearing on said journal-cap, substantially as set forth.

In testimony whereof we affix our signatures in presence of two witnesses.

ALBERT BUCHNER.
ELMER P. McCLURE.
